9 Claims. (Cl. 102—7.2)

1

This invention relates to bombs, and more particularly to adapters for clustering bombs.

The present invention provides an adapter for clustering bombs in which the parts thereof, when released from a cluster of bombs after it is free of a plane, fall at approximately the same speed and approximately the same trajectory as the bombs in the cluster.

Bomb clustering adapters of the present invention are suitable for both high and low level bombing, because the apparatus comprises relatively few parts, all of which have essentially the same flight characteristics as the bombs in the cluster. Since the flight characteristics of the adapter are essentially the same as that of the bombs, the adapter may be released from the bombs immediately after the cluster is discharged from the bomb bay of a plane and the parts of the adapter will not constitute a danger to other planes in the flight formation or in succeeding flight formations.

The present invention provides a bomb clustering adapter which is used with aimable bombs since the adapter can be released from the cluster immediately after the bombs clear the bomb bay of a plane.

The invention will be understood from the following description when considered in connection with the accompanying drawings forming a part thereof, and in which—

Fig. 1 is a perspective view of an adapter for clustering bombs embodying the present invention taken from the forward end thereof;

Fig. 2 is a view similar to Fig. 1, but from the rearward end of said bomb;

Fig. 3 is a longitudinal sectional view of a carrier bar of the adapter taken on the line 3—3 of Fig. 4;

Fig. 4 is an enlarged transverse sectional view taken on the line 4—4 of Fig. 3;

Fig. 5 is a sectional view taken on the line 5—5 of Fig. 3;

Fig. 6 is a longitudinal sectional view of a stiffening bar of the clustering apparatus;

Fig. 7 is a view similar to Fig. 5, but of another stiffening bar, and

Fig. 8 is an elevational view of the extensible tail retaining means.

Like characters of reference refer to like parts throughout the several views.

Referring to Figs. 1 and 2, the adapter of the present invention comprises a carrier bar 10 in which is anchored a plurality of bomb holding cables 11. The cables extend around a cluster of bombs 12 which cluster is braced by a plurality of

2

stiffening bars 13 spaced circumferentially of the cluster and extending longitudinally thereof. Bars 13 are held in the cluster by cables 11 and maintain the forward group and rearward group of bombs in the cluster in longitudinal alignment.

The carrier bar 10 is shaped substantially like a bomb and comprises a tubular body portion 15 having a nose 16 at the forward end thereof secured to body 15 by welding 17. Nose 16 contains firing mechanism 18 which, as shown, consists of a time fuse 19 having a primer cap 20 at one end thereof. At its opposite end, the fuse is in communication with an ejecting charge within a container 21. Fuse 19, cap 20 and container 21 are mounted in a fuse body 22 screw-threaded into the nose 16. In axial alignment with the cap 20, is a firing pin 23 having a head 24 with a point 25 thereon. The firing pin has longitudinal movement in the nose 16 and is caused to move toward the cap 20 by a spring 26 which bears against a collar 27 on the firing pin. The firing pin 23 has a substantially U-shaped cut-out portion 23' therein, one leg of which bears against a longitudinal edge of a flat portion 28' of an arming pin 28 (Figs. 3 and 5) which extends through the wall of the nose 16 of the bomb. The arming pin 28 normally holds the firing pin in such position that the head 24 thereof and the pin 25 are spaced from the cap 20 against the tension of the spring 26, the pin 28 being held against rotation by an arming wire 26' which extends through the head of the pin 28, the opposite ends of the wire being held in an aperture 35 in the wall of the nose which aperture is slidably engaged by the wire. When the arming wire 26' is withdrawn, the tension of the spring 26 causes the arming pin to rotate permitting the longitudinal edge of the flat portion 28' to disengage the U-shaped cut-out portion 23' of the firing pin so that the tension of the spring 26 will cause the head 24 and point 25 to impact the cap 20.

The fuse body 22 extends into a passage 68 in an extension 69 which extension is also attached to the nose by screw-threads. Cap 67 slidably engages the passage 68 and fuse body and fits over the end of the fuse body in which the ejecting charge container 21 is positioned. Piston 29 is slidably mounted in the passage 68 and has a head 30 at one end thereof and a reduced portion 31 at the opposite end forming a shoulder 32 between said portions. A mounting tube 14 extends longitudinally of body 15, one end thereof slidably engaging the reduced portion 31 of the piston and abutting shoulder 32 thereof.

while the opposite end of the tube is positioned in head 33 of a mounting member 34 which mounting member slidably engages the rearward end 35 of the carrier bar and is normally so positioned that head 33 is in spaced relationship with end wall 36 of the end 35.

Carrier bar 10 has an extensible tail structure to guide it on its flight. The extensible tail structure comprises a finned tail 38 secured to a rod 39 which extends into the tube 14 through rearward end 35 of the carrier bar. The rod 39 is held in position in the carrier bar by the shear wire 42 which maintains the bushing 40, secured to the rod by screw-threads 41, in position in the end 35 against the tension of spring 37 which engages collar 44 and reduced portion 31 of piston 29. A nut 43, which engages the screw-threads 41 on the rod 39, secures the tail 38 on said rod. The head 33 of the mounting member 34 has a substantially conical-shaped aperture 74 therein into which a substantially conical-shaped stop 75, which is fixedly mounted on the rod 39, tightly fits. The stop 75 limits the movement of the rod toward the end 35 and, when positioned in the aperture 74, steadies the extensible tail, as will hereinafter be fully described.

Latches in the carrier bar 10 hold the cables 11 in position around the bomb cluster until the latches are actuated to release the cables. A latch 45 for each cable is secured to and movable with the mounting tube 14 and has passages 46 and 47 therein which extend longitudinally thereof and axially of the tube 14 at opposite sides of the body. The passages, as shown, taper from the end thereof adjacent the shoulder 32, where the area is the greatest toward the opposite end where the area is the smallest. Slot 48 in the passage 46 extends axially thereof and has a portion 76 of restricted width and a portion 77 of enlarged width. Passage 47 has a slot 49 therein extending axially thereof which slot is of a restricted dimension throughout its length. The cables 11 have balls 50 and 51 connected to the opposite ends thereof and are of a diameter less than the greatest diameter of the passages 46 and 47 and greater than the smallest diameter of said passages. The ball 50 is positioned in the passage 46 and is of a diameter greater than the width of portion 76 and less than the width of portion 77. The ball 51, which is positioned in the passage 47, is of greater diameter than the width of slot 49. The cables to which the balls are attached extend outwardly of the latches 45 through the slots 48 and 49 and outwardly of the carrier bar through apertures 52 and 53 respectively in the body 15 of said carrier bar. The aperture 52 is of greater diameter than the ball 50 so that the ball may pass freely through it while the aperture 53 is of lesser diameter than the ball 51 so that the ball 51 will at all times be retained in the passage 47. So that the bomb cluster may be hoisted into the bomb bay of a plane, lugs 54 and 55 are attached to the upper part of the body 15 of the carrier bar 10.

The stiffening bars 13 are also shaped similarly to a bomb and, as shown in Fig. 6, comprise a tubular body 56 having a nose 57 of heavy metal, such as cast iron or lead, secured thereto which nose, as shown, is rounded at its forward end. The rearward end of the stiffening bars is tapered at 58 and has a finned tail 59 attached thereto by a bolt 60 which engages a cone 61 within the body 56 so that the cone may be drawn tightly within the body.

The stiffening bars 13 may be constructed for

use as a bomb and may contain explosive, incendiary or smoke-making substances. As shown in Fig. 7, the stiffening bar 13 is constructed as a smoke bomb by inserting a cartridge 62 containing smoke-making substance which is fired by an inertia fuse 63. The tail portion of the body 56 has smoke vents 65 therein. Smoke, after the cartridge is fired by the inertia fuse 63 when the bomb strikes an object, passes outwardly of the cartridge through outlets 66, thence outwardly of the body 56 through the vents 65.

Tie rods 64 (Fig. 8) are positioned in the bomb cluster and extend longitudinally of the cluster to maintain the extensible tails of the bombs in position. The tie rods comprise a rod 70 having a pointed head 71 disposed adjacent the nose of the bombs and of a dimension greater than the space between the noses of adjacent bombs and a tail at the opposite end thereof. The tail comprises three fins 72 spaced apart so as to engage the adjacent tail surfaces of three adjacent bombs as shown in Fig. 2. A washer 73 engages the end of the bomb tail and acts to retain the extensible tail in position until the declustering of the bombs.

In operation, the bombs 12, which are hexagonally-shaped, are formed into a cluster as shown in Figs. 1 and 2, with the carrier bar placed between two adjacent bombs at the periphery of the cluster and the tie rods 64 positioned within the cluster, both the carrier bar and the rods extending longitudinally thereof. Stiffening bars 13 are also positioned between two adjacent bombs at the periphery of the cluster to extend longitudinally thereof in spaced relationship to the carrier bar and with each other. The cables 11 are then placed around the cluster the opposite ends thereof being positioned in the latches 45. The cables have a turnbuckle 78 intermediate the opposite ends thereof. The turnbuckles 78 are then tightened so that the carrier bar and stiffening bars are tightly positioned in the cluster and the bombs are retained in position in the cluster by the clustering apparatus comprising the carrier bar, cables, tie rods and stiffening bars. The bomb cluster is then hoisted into the bomb bay of a plane, the bomb carrying mechanism in the plane engaging the lugs 54 and 55.

Before release from the bomb bay of a plane, the various parts of the carrier bar 10 are in the position shown in Fig. 3. Upon release of the bomb cluster from the bomb bay, the arming wire 26 is withdrawn causing the arming pin 28 to be rotated in a clockwise direction (Fig. 5) by tension of the spring 26 which permits the spring 26 to act on the firing pin 23 moving it in a direction toward the primer cap 20 and causing the point 25 and head 24 to impact and detonate said cap. Detonation of the primer cap sets off the time fuse 19 which burns toward the ejection charge in the container 21. Normally, the fuse is such that the ejection charge will be detonated within a relatively short period of time after the bomb cluster is released from the plane, for example approximately two seconds. Detonation of the ejection charge in the container moves the fuse body cap 67 toward the tail of the carrier bar which causes the piston 29 to move in the same direction. Movement of the piston 29 toward the tail of the carrier bar 10 moves the tube 14 and the mounting member 34, the head 33 of which is engaged by the opposite end of the tube 14, toward the tail of the carrier bar. En-

gagement of the head 33 of the mounting member with the end wall 36 of the end 35 limits the movement of the mounting tube 14 and mounting member 34.

Movement of the mounting member 34 toward the tail causes the shear wire 42 to be broken and the bushing 40 to be released from the end piece 35, the bushing and the rod 39 to which it is attached being moved rearwardly of the end piece and the carrier bar. When the bushing 40 is free of the end piece 35, the spring 37, which is under tension and bears on the collar 44, moves the rod 39 to the right, Fig. 3, until the conical-shaped stop 75 engages the conical-shaped aperture 74 in the head 33 of the mounting member 34 thereby extending the tail 38 beyond the end of the carrier bar. The tension of the spring 37 is such that the stop 75 is tightly maintained in the aperture 74 thereby steadyng the extensible tail.

The latches 45 are moved in a direction rearwardly of the carrier bar by the detonation of ejection charge in container 21 since the latches are attached to the tube 14. This movement of the latch members releases the ball 50 on the cables 11 from the passage 46, the ball 50 passing from the area of smaller diameter of the passages 46 into the area of greater diameter of said passage. The ball 50 moves, at the same time, beyond the portion 76 of restricted width of the slot 48 and to a point adjacent the portion 77 of enlarged width thence outwardly of the latch through the enlarged portion 77. Release of the ball 50 from the latch members causes the ball to pass outwardly of the body 15 through the aperture 52 thereby releasing the cables 11 from around the stiffening bars 13 and from around the bomb cluster which declusters the bombs 12. The ball 51 is maintained in the latch 45 as it is of greater diameter than the width of the slot 49. The cables 11, therefore, remain attached at their opposite end to the carrier bar and fall with said bar. Since the carrier bar 10, stiffening bars 13, and the rods 64 are of the general construction of a bomb, they will have substantially the same flight characteristics as a bomb, and will fall at approximately the same speed and approximately the same trajectory as the bombs in the cluster.

While a preferred embodiment of the present invention has been shown and described, it will be understood that the invention is not limited to the precise details shown. For example, any well-known type of firing mechanism may be used in the carrier bar to set off the ejection charge and in the stiffening bars to ignite the smoke-making or other substance. The nose or tail structure of the carrier bar and stiffening bars may be of a type well-known in the construction of bombs.

Since changes may be effected in the form of the invention selected for disclosure without departing from the principles of the invention, it will be understood that the invention is not to be limited excepting by the scope of the appended claims:

What is claimed is:

1. Bomb clustering apparatus comprising a bomb-shaped member having a nose, a body portion and a tail, a bomb holding band to extend around a plurality of bombs and hold them in a cluster, explosive containing means in the member, an explosive in said containing means, firing means for detonating an explosive, a piston in said member adjacent the explosive containing

means and operative by the explosive force of the explosive in a direction away from the containing means, an elongated member extending longitudinally of the bomb-shaped member in a direction away from said containing means and movable longitudinally therein by said piston, and latching means mounted on the elongated member for movement therewith and adapted to releasably receive one end of the band, the arrangement being such that movement of the piston by said explosive force causes the elongated member and the latching means to move and release said one end of the band thereby freeing the band from around said cluster.

2. Bomb clustering apparatus comprising a bomb-shaped member having a nose, a body portion and an extensible tail, a plurality of bomb holding bands to extend around a plurality of bombs and hold them in a cluster, explosive containing means in the member, an explosive in said containing means, firing means for detonating an explosive, a piston in said member adjacent the explosive containing means and operative by the explosive force of the explosive in a direction away from the containing means, an elongated member extending longitudinally of the bomb-shaped member in a direction away from said containing means and movable longitudinally therein by said piston, latching means mounted on the elongated member for movement therewith and adapted to releasably receive one end of the bands, and means for extending said extensible tail operative by movement of said elongated member, the arrangement being such that movement of the piston by said explosive force causes the elongated member and latching means to move and extend said extensible tail and release said one end of said bands thereby declustering the bombs.

3. Bomb clustering apparatus comprising a bomb-shaped member having a nose, a body portion and an extensible tail, a plurality of bomb holding bands to extend around a plurality of bombs and hold them in a cluster, explosive containing means in the member, an explosive in said containing means, firing means for detonating an explosive, a piston in said member adjacent the explosive containing means and operative by the explosive force of the explosive in a direction away from the containing means, an elongated member extending longitudinally of the bomb-shaped member in a direction away from said containing means and movable longitudinally therein by said piston, latching means mounted on the elongated member for movement therewith and adapted to releasably receive one end of the band, means in said cluster for holding the tail in its unextended position, and means for extending said extensible tail operative by movement of said elongated member, the arrangement being such that movement of the piston by said explosive force causes the elongated member and latching means to move releasing said one end of said bands thereby declustering the bombs and extending said extensible tail.

4. Bomb clustering apparatus comprising an elongated member having a nose at one end, a tail at the opposite end and a body portion intermediate the opposite ends of said member, the body portion having a longitudinally extending chamber therein, an explosive in the member adjacent one end thereof, firing means in said member associated with and adapted to detonate the explosive, a plurality of bomb holding

bands spaced from one another longitudinally of said elongated member, said bands being of a length to extend circumferentially of a cluster of bombs and normally retain them in clustered relationship, mounting means disposed in said chamber for longitudinal movement therein, actuated means in the member positioned between said explosive and the mounting means for longitudinal movement toward the mounting means, said actuated means being so disposed that detonation of said explosive causes the actuated means to move longitudinally and impart longitudinal movement to said mounting means, means normally holding said mounting means against movement, band securing means associated with each of said bands to normally maintain the bands in position around the cluster, each of said band securing means being mounted on said mounting means for movement therewith, said band securing means comprising latching means adapted to normally releasably hold one end of a band and release said one end of a band upon longitudinal movement of the mounting means by detonation of the explosive, means in said cluster for normally holding the tail in its unextended position, and means for extending said extensible tail operative by movement of said mounting means.

5. Bomb clustering apparatus comprising an elongated member having a nose, a body portion and a tail, a bomb holding band having opposite ends and normally extending around a plurality of bombs to hold them in a cluster, an enlargement on at least one end of said band, said member having an opening through which the enlargement enters and passes from the member, latching means mounted within said member for longitudinal movement in relationship thereto, said latching means comprising a body adapted to retain one end of said band in the member at all times and having a longitudinal slot to normally releasably hold the opposite end of the band in said member, the slot being of a dimension less than the size of said enlargement adjacent one end thereof and of a dimension greater than said enlargement in the direction away from said one end of the slot opposite to the direction of longitudinal movement of the latching means, explosive containing means in the member, an explosive in said containing means, firing means for detonating said explosive in said explosive containing means, and actuated means mounted for longitudinal movement in said member and cooperating with the latching means, said actuated means being operative by the explosive force of the explosive longitudinally of the member toward the latching means to act thereon and move said latching means longitudinally in the member thereby permitting the enlargement on said opposite end of the band to become released from the portion of the slot of greater dimension than the enlargement and pass outwardly from the member and from around the bombs to decluster said bombs.

6. Bomb clustering apparatus comprising a bomb-shaped member having a nose, a body portion and a tail, a bomb holding band to extend around a plurality of bombs and hold them in a cluster, an enlargement on at least one end of said band, the member having an opening through which the enlargement enters and passes from the member, explosive containing means in the member, an explosive in said containing means, firing means for detonating an explosive, a piston in said member adjacent the explosive containing

means and operative by the explosive force of the explosive in a direction away from the containing means, an elongated member extending longitudinally of the bomb-shaped member in a direction away from said containing means and movable longitudinally therein by said piston, and latching means mounted on the elongated member for movement therewith, said latching means comprising a body adapted to retain one end of said band in the member at all times and having a longitudinal slot to normally releasably hold the opposite end of the band in said member, the slot being of a dimension less than the size of said enlargement adjacent one end thereof and of a dimension greater than said enlargement in the direction away from said one end of the slot opposite to the direction of longitudinal movement of the latching means, the arrangement being such that movement of the piston by said explosive force causes the elongated member and the latching means to move longitudinally of the member permitting the enlargement on said opposite end of the band to become released from the portion of the slot of greater dimension than the enlargement and pass outwardly from the member and from around the bombs to decluster said bombs.

7. Bomb clustering apparatus comprising an elongated carrier member, a bomb holding band to extend around a plurality of bombs and hold them in a cluster, explosive containing means in the member, an explosive in said containing means, firing means for detonating an explosive, a piston in said member adjacent the explosive containing means and operative by the explosive force of the explosive in a direction away from the containing means, another elongated member extending longitudinally of the carrier member in a direction away from said containing means and movable longitudinally therein by said piston, and latching means mounted on the elongated member for movement therewith and adapted to releasably receive one end of the band, the arrangement being such that movement of the piston by said explosive force causes the elongated member and the latching means to move and release said one end of the band thereby freeing the band from around said cluster.

8. Bomb clustering apparatus comprising an elongated carrier member having a body portion intermediate the opposite ends of said member, the body portion having a longitudinally extending chamber therein, an explosive in the member adjacent one end thereof, firing means in said member associated with and adapted to detonate the explosive, a plurality of bomb holding bands spaced from one another longitudinally of said elongated member, said bands being of a length to extend circumferentially of a cluster of bombs and normally retain them in clustered relationship, mounting means disposed in said chamber for longitudinal movement therein, actuated means in the member positioned between said explosive and the mounting means for longitudinal movement toward the mounting means, said actuated means being so disposed that detonation of said explosive causes the actuated means to move longitudinally and impart longitudinal movement to said mounting means, means normally holding said mounting means against movement, band securing means associated with each of said bands to normally maintain the bands in position around the cluster, each of said band securing means being mounted on said

mounting means for movement therewith, said band securing means comprising latching means adapted to normally releasably hold one end of a band and release said one end of a band upon longitudinal movement of the mounting means by detonation of the explosive, a tail at one of said opposite ends of the carrier member, means in said cluster for normally holding the tail in its unextended position, and means for extending said extensible tail operative by movement of said mounting means.

9. Bomb clustering apparatus comprising an elongated carrier member, a bomb holding band having opposite ends and normally extending around a plurality of bombs to hold them in a cluster, an enlargement on at least one end of said band, said carrier member having an opening through which the enlargement enters and passes from the member, latching means mounted within said member for longitudinal movement in relationship thereto, said latching means comprising a body adapted to retain one end of said band in the member at all times and having a longitudinal slot to normally releasably hold the opposite end of the band in said member, the slot being of a dimension less than the size of said enlargement adjacent one end thereof and of a dimension greater than said enlargement in the direction away from said one end of the slot opposite to the direction of longitudinal movement of the latching means, explosive containing means in the member, an explosive in said con-

taining means, firing means for detonating said explosive in said explosive containing means, and actuated means mounting for longitudinal movement in said member and cooperating with the latching means, said actuated means being operative by the explosive force of the explosive longitudinally of the member toward the latching means to act thereon and move said latching means longitudinally in the member thereby permitting the enlargement on said opposite end of the band to become released from the portion of the slot of greater dimension than the enlargement and pass outwardly from the member and from around the bombs to decluster said bombs.
